SHIP LAUNCHING WAYS ASSEMBLAGE

Blakely Smith, Houston, Tex.

Application November 25, 1942, Serial No. 466,897

6 Claims. (Cl. 61—67)

This invention relates to improvements in ship launching ways, and has particular relation to launching ways designed to permit sidewise launching of ships.

During recent years the method of launching ships in their direction of length has been modified in various yards by providing the ship construction in such way as will permit the ship to be launched sidewise instead of lengthwise. Certain advantages are presented by this change amongst which is the fact that while the same dimensioned ship may be present in both forms of launching, the longitudinal or endwise launching requires a basin or harbor with a dredged zone of great width from the shore line—to permit the entire length of the ship to pass thereto when being launched—and with the dredged depth sufficient to permit the passage of the ship downward on the ways into its buoyant status in the water without liability of grounding. This method of launching ships has been the practice through the years, but the ship-building needs of recent years requiring additional facilities, led to the development of the practice of launching the ships sidewise—in which the width of the ship becomes the criterion as to dredging width and depth along the shore instead of the length, the latter dimension being taken care of by the usual maneuvering and other areas required by the earlier practice; with sidewise launching the entire length of the ship from bow to stern zones contacts the water substantially concurrently throughout the length, instead of by the gradual stage-like contact of the earlier practice. Hence, the sidewise launching reduces the dredging needs, and while it requires the use of a plurality of ways—from four to thirty, dependent on the length and tonnage of the ship—these are ashore and therefore require no special dredging. In addition, the maneuvering area required to bring the launched ship to rest is much less with the sidewise launching, as is apparent.

Two different forms of sidewise launching have been employed heretofore. One of these forms has the ground ways extending to the water's edge and fixed; in this form the sliding ways, during launching, continue to advance along and beyond the fixed ways until the ship's weight causes the sliding ways and ship to drop off of the fixed ways into the water. In the second form the lower ends of the ground ways are loose and arranged relative to a fulcrum knuckle, the loose ways tilting as the weight of the ship causes preponderance on the water's edge side of the loose ways. Both forms are in use, and each has

ardent advocates. But both have certain disadvantages, amongst which is the fact that in both the launching causes a decided rolling effect on the launched ship, due to the canted position when reaching the surface of the water, and the ship, in righting itself, exposes the inboard bilges to the possibility of being damaged by the bulkhead or the ends of the fixed ways.

The present invention is designed to permit sidewise launching without liability of damaging such bilges, and, in addition, to permit such launching under conditions where adequate depth of water is not obtainable in the immediate vicinity of the ends of the fixed ways. The result is obtained by the use of a buoyant extension of the fixed ground ways, with the extension pivoted relative to the latter and having its free end tethered to the bed of the basin by a flexible connection, with the latter of such length that the buoyant section, in its upper position, will form a direct continuation of the fixed ground ways; in the latter position, all but an inner zone of the buoyant section is permanently submerged, the length of the unsubmerged inner zone depending upon the height of the outer ends of the fixed ground ways above the water level of the basin; in practice, it is preferred that the water level practically extend to the height of the outer end of the fixed ground ways, in which case the buoyant section is completely submerged. The buoyant section is of such form and arranged in such manner as to swing arcuately downward on the pivot at its inner end and may come to rest on the inclined bed of the basin adjacent the shore line. The buoyant section is of a type to provide for positive buoyancy so that it normally remains in its upper position, remaining in that position during the downward travel of the sliding ways carrying the ship, until the centre of gravity of the moving mass passes the pivot point, whereupon the buoyant section will lower under the weight of the moving mass, moving in such arcuate path.

Obviously, the successful operation will depend somewhat upon the rate at which the section is lowered. Since the advance of the moving mass constantly increases the weight placed on the section, and the lowering action constantly changes the angle of the top of the section to increase its angularity to the horizontal, it is apparent that unless resistance additional to that of the normal positive buoyancy be present, the rate of lowering will increase very rapidly despite the positive buoyancy; while such positive buoyancy would, in itself, be of advantage—in that

the ship would have been carried a greater distance from the shore line before entering the water—the invention contemplates a retardation in the rate of lowering. This is provided by employing a "flooring" in the outer zone of the section, the width of the flooring zone being such as to offer a large area of resistance to the downward movement, thus decreasing the rate of the downward movement of the buoyant section as the ship advances during the launching and easing the lowering of the ship into the water.

This easing of the lowering movement is additionally facilitated through the character of the launching activities provided by the sidewise launching of the ship. This launching method utilizes a plurality of individual ways spaced apart in the length of the ship—the number of ways will vary, being dependent on the length and tonnage of the ship; hence, the number may range from four to thirty individual ways. By continuing the flooring characteristic between ways—the flooring being carried from way to way as well as in the way itself—the combined ways not only provide the resistance set up by the positive buoyancy of the way together with the flooring zone of such way, but, in addition, the flooring connection between ways adds to such resistance, since it will be necessary for this portion also to be forced downward through the water during lowering of the section. In other words, the combined spaced-apart ways include a zone having a predetermined width and a substantially continuous length and in which the planar face of the flooring must move through the water in a direction which is at substantial right angles to the plane of the face, thus providing a retarding agency active in opposition to the weight of the ship being launched.

In addition, the connection of the ways through the flooring zone serves to ensure that all of the ways of connected groups will move in unison, ensuring that the ship launching will be substantially uniform from bow to stern. In other words, while the ship may vary in weight characteristic in the direction of its length and thus tend to place unequal pressures on different ways, the fact that the active ways of an extended length zone are positively connected together through the flooring tends to reduce the effect of such weight variations, since the flooring must move as a unit and the resistance of the less weighty portions aid in producing an equal resistance to the lowering of the heavier portions of the ship. As a result, the launching is not only under more favorable conditions, but there is no likelihood of strains being placed on the ship itself such as could result from unequal rates of lowering movement where unconnected and spaced ways are utilized.

To these and other ends, the nature of which will be made clear hereinafter, the invention consists in the improved constructions and combinations of parts hereinafter more fully described, illustrated in the accompanying drawings; and more particularly pointed out in the appended claims.

In the accompanying drawings, in which similar reference characters indicate similar parts in each of the views—

Figure 1 is a view of an end of a battery of ways, parts being shown in section, and designed for practicing the invention.

Fig. 2 is a detail sectional view taken on line 2—2 of Fig. 1, showing one form in which the

sliding and fixed ground ways may be arranged for co-operation.

Fig. 3 is a transverse sectional view taken on line 3—3 of Fig. 1, to illustrate one way in which the buoyant section may be formed.

Fig. 4 is a diagrammatic plan view of a portion of the battery of units used in sidewise launching of ships under the invention.

Since the present invention is designed for the launching of ships sidewise instead of lengthwise, it is apparent that the launching ways assemblage must present a structure capable of efficiently supporting the boat from bow to stern during the launching. Obviously, where the ship is of considerable length the cradle structure—if used in building the ship—would extend throughout such length, but it would not be necessary that the ways used in launching the ship would require an equally lengthy continuity, although such continuity is obtainable and may be employed herein; however, it is possible to efficiently support the cradle and keel by the use of individual sliding way units, spaced apart in the direction of length of the ship, provided the spacing does not present a span effect on the ship sufficient to cause the latter to be strained. Hence, practice has demonstrated that if the battery of launching ways have a sufficient number of individual ways—sliding and supporting ways—to meet the tonnage conditions of the ship and prevent undesired strains, the ship can be launched sidewise, and thereby make possible the use of plant locations such as could not be employed with lengthwise launching excepting through the use of vast dredging operations; frequently, such operations would not be feasible at a particular location which otherwise would be ideal for service as a ship-building yard. Conditions such as this have led to the idea of arranging the yards at such latter locations and then arrange for sidewise launching of the ships, even to such an extent as to make such course one of the modern developments of ship-building.

As heretofore pointed out, the launching ways heretofore used in this connection, have utilized either one or the other of two general fundamental methods. Both utilize fixed ground ways for each unit, these extending to the vicinity of the shore line, and on which the sliding way is located, the fixed way being inclined downwardly, with the sliding way having its lower face corresponding to the angle of the ways; while the upper face is horizontal, since on this face the boat construction is developed. In one of the methods the ground ways extend to the shore line, and in launching, the sliding ways are released and travel downward over and in complete contact with the fixed ways until the centre of gravity passes beyond the end of such fixed ways, whereupon the preponderance of weight causes the sliding ways to cant rapidly with the ship moving off of the ways into the water.

The second method varies this by having the fixed ground ways extend to the vicinity of the shore line with the remainder of the distance taken care of by the use of rocking ways which project over the shore line, the rocking section being mounted on an intermediate fulcrum which permits the way to present a continuation of the fixed way—thus permitting the sliding ways to move properly to the water's edge; when, however, the center line of the ship passes beyond the fulcrum point, the entire section rocks on the fulcrum; thus immediately shifting the slid-

ing way and the ship to the angle at which the ship is being launched.

Both of these methods have their partisan adherents and both possess certain advantages; but both also have their disadvantages amongst which is the fact that, with both, the angle present during the latter part of the launching is such that the ship is careened to a considerable angle when entering the water, with the result that, in righting itself, the tendency is to cause the ship to roll to a careening angle in the opposite direction; if the roll takes place close to the shore line, there is a possibility that the inboard bilge portions of the ship will be carried into contact with the piling, etc., of the shore-line bulkhead, by the roll of the ship, with the possibility of such bilge portions being damaged. This possibility of damage is one of the objectionable features emphasized by the opponents of sidewise launching.

The present invention meets this condition by varying the launching technique during the latter part of the launching from that found in these two methods. The objectionable feature referred to appears to come from the fact that in both methods the center line of the ship is caused to shift or swing about a pivot or its equivalent at a rapid rate, thereby causing the ship to reach the water surface while such center line is canted to a considerable extent, with the weight of the ship active in producing a rapid drop of the ship into the water, thus bringing the initial water contact high up on the outboard side of the ship and with the ship located in the vicinity of the shore line. Hence, when the submerging of the ship's bottom takes place with the resultant effort of the ship to return its center line to the vertical, the latter action carries such line to the opposite side of the vertical, and, due to the proximity of the ship to the shore line, the action tends to bring the inboard bilge portions into contact with the bulkhead. In other words, the initial wetting of the ship on the outboard side reaches to such a point that the righting of the ship causes sufficient power to cause the ship to seriously roll in the opposite direction—results due to the large angularity of the drop—and since the drop takes place in the vicinity of the bulkhead, the inboard bilge portions are moved beyond a position of safety.

While the present invention provides for a pivotal movement of ways and thus changes the angle of advance, the rate of change of the latter angle is reduced, with the result that the ship not only has its initial contact with the water farther from the shore line, but the rate of swing of the center line of the ship is reduced to such an extent that the angle of the center line to the vertical at such moment of contact is materially less than with the methods referred to, with the result that during the righting of the ship to the extent of the roll is greatly decreased, if not rendered negligible, and, when present, takes place at a greater distance from the shore line and wholly within the safe limits of the launching basin, thus avoiding any liability of damage to the inboard bilge portions.

An assembly designed to produce this and other results is shown illustratively in the accompanying drawings, these showing one specific form in which the assembly may be produced. Obviously, the details may be varied, since alternative ways of meeting specific problems are well-known. For instance, the specific

form of the opposing faces of the sliding way and the fixed ways may be either of a number of such forms which may be employed, but all of which have the general characteristic of permitting the sliding way to travel forward in a fixed path to ensure that there is no lateral movement of the sliding way during the travel—one such form is shown, but it is obvious that other forms may be employed and which are designed to provide similar results. Similarly, the buoyant section may present either of a number of different structural forms as long as they present the fundamental characteristics of a positive buoyancy and of the retarding feature—one detail form is shown but other well-known structural forms may be employed, including, if desired, special buoyancy-producing means designed to produce the positive buoyancy characteristic referred to. And, obviously, the buoyant section will present the same type of co-operating face as shown by the fixed ways, since the sliding ways co-operate with both the fixed ways and the ways of the buoyant section during the launching. In other words, the invention is not limited to the specific details shown, the latter being illustrative of the fundamental features upon which the invention rests.

In the drawings, A represents the ship; B indicates the sliding ways; C indicates the fixed ground ways; D indicates the buoyant section, and E indicates the launching basin.

In principle, the length and tonnage of the ship will determine the number of ways employed. For instance, a very heavy ship may require as many as twenty-eight fixed ground way units, while a smaller ship may require as few as six of such way units; because of this the invention contemplates the use of a plurality of ground way units ranging in number from four to thirty. In this reference to ways and way units, the term is designed to include the assemblage of B, C and D, which constitute the support for the ship; however, the term "supporting unit" herein refers more particularly to elements C and D over which the element B and the ship advance during the launching. This distinction is made due to the fact that the sliding way B may be continuous and have a length to include a number of supporting units, as presently explained; or may be of a length co-operative with but a single supporting unit, in which case it would form—with the supporting unit—a "ship's supporting unit" rather than the "supporting unit" referred to, element B forming part of the support for the ship and at the same time is advanced with the ship during launching of the latter.

The sliding way B will have a definite area, the width determined by the width of the ship, while the length will be determined by whether it is used individually with a single supporting unit or concurrently cooperates with a succession of such units. The fixed ground ways C will have their directions of length transverse to the direction of length of the ship, and have a length sufficient at least to reach from the shore line to the rear of the sliding way, whether the latter be individual to a single supporting unit or include a succession of such units. The fixed ground ways of a supporting unit may be two or more in number—preferably two—being spaced apart and extending in parallelism, the total number of ways C used being such as to provide for adequate support for the ship,

these presenting a succession of supporting unit elements with the latter also spaced apart. The buoyant section D of a supporting unit will have a width substantially equal to the overall width of the ways C which form the supporting unit; the section length will generally have a length approximating the width of the sliding ways B, although such entire length may not be needed during launching—in practice, its length is such as to ensure proper launching of the largest ships contemplated by the launching assemblage. The ground ways C reach to the bulkhead e of the basin e', and the buoyant section D is pivoted relative to the ground ways C at that point, with the arrangement such that during the inactive period of the launching assemblage, the "ways" of the ground portion of the supporting unit, and those of the buoyant section of such unit, will extend in a common plane—downwardly-inclined relative to the horizontal—from end to end. If the number of "ways" of a supporting unit is greater than two, an equal number will be provided on the unit buoyant section.

In practice, the supporting units are spaced apart, the spacing distance depending upon the weight characteristic of the ship. Each unit is considered as an individual, in that the elements referred to are cooperative with each other. However, the buoyant sections each include a flooring portion—presently referred to in detail—and this element is designed to connect adjacent units together, so that, in this respect, there is co-operation between units; additional co-operation between units will be present where the sliding way assemblage is itself continuous instead of formed of individual portions tied together by the ship itself. This connection of supporting units by the flooring—to form groups of units—will also depend—for its grouping characteristic—on the weight of the ship. For instance, if the number of units required is six for the ship being launched, all of these may or would be grouped into one unit group; on the other hand, if the ship is of a size to require twenty-eight supporting units, these may be divided into four unit groups by connecting together seven adjacent units into a single group. These are illustrative to indicate the general flexibility of the invention; it is apparent that as many as seven supporting units may be grouped into a single unit group, and, therefore, the total number of units which may be required for a particular ship's tonnage can be divided into unit groups the number of which is best qualified to produce the desired result operationally.

The slide-ways B are necessarily held against movement longitudinally of the ship, as well as be able to slidily advance lengthwise of the supporting ways. Hence, as indicated in Fig. 2, the under face of the slideway and the upper face of each ground way are provided with suitable complementary configurations such as will permit these activities when the sliding way assemblage is released at the start of the launching. The particular form of complementary faces shown is that of a simple projecting ridge c, of inverted V-shape in cross-section, carried by the ground way C, with the under face of the sliding way grooved, as at b; the number of grooves b will depend upon the number of ground ways used with a sliding way. This particular form is simply illustrative of a number of complementary configurations which may be employed. Since the fixed ground ways C are downwardly inclined toward the bulkhead to permit the launch-

ing to take place under the usual sliding conditions produced by the weight of the ship, the under side of the sliding way is preferably arranged at a complementary angle to the horizontal, while the top face generally extends horizontally in order that the ship construction may take place on the basis of an even keel, with the center line of the ship extending vertically. A cradle may be employed, if desired, but is not shown herein as it forms no part of the present invention.

The structure of the sliding way is shown in its simplest form and, as shown, is not to be considered as of limiting effect, since it is obvious that, structurally, it can be made up in a variety of ways; when formed of a suitable wood content, and more or less solid, it can present buoyant characteristics such as tend to reduce the total weight characteristic of the ship during the latter part of the launching operation; however, the structure must have sufficient strength to maintain itself during the building and launching operations.

The buoyant section of each unit may be of suitable form, that disclosed illustratively herein being generally of truss characteristic. Since two "way" formations are found in the fixed ground ways, it is apparent that section D will provide a similar number of "ways," these being in lengthwise alignment to those of the ground ways C. As a result, the truss formation will not only have a depth dimension but also a width dimension, with the truss members connected to provide the width of the section. The width of the section will generally approximately equal the overall width of the "ways" of the ground ways portion of the supporting unit; if the sliding way assemblage be of the "ship's supporting unit" type, the width of section D may equal the length of the sliding way unit member.

The buoyant section D of the supporting unit is hingedly or swingingly connected at its inner upper end to the bulkhead ends of the fixed ground ways, or to the upper zone of the bulkhead e; in the latter case, the ways of section D, in the normal upper position of the latter, will align with the ways of the fixed ground ways to form a continuation thereof. The hinging points are indicated at d. The outer end of section D is tethered to the bottom or bed of the basin E in suitable manner, a flexible cable or chain d' being shown as having its lower end anchored to the bottom of the basin and its upper end secured to the bottom of the truss; the length of the cable or chain is such that when the section is in its upper position, its ways will form a continuation of the fixed ground ways of the unit—since the latter are inclined downwardly, the continuation provided by section D will also be inclined at the same angle to the horizontal when in such position. In other words, with section D in its upper or raised position, a continuous way characteristic is provided from the inner end of the fixed ground ways to the outer end of the buoyant section, with the ways inclined downward at uniform angle to the horizontal.

Since section D is hingedly mounted at its inner upper end, it is apparent that the section can swing downwardly from such upper position through an arc the center of swing of which is the hinging points d. The truss is therefore arranged with oblique inner and outer ends to enable the section to swing through such an arc, the length of the arc being such that when the lower portion of the truss is in contact with the

bed of the basin, a ship of the largest dimensions will have reached at least the neighborhood of its launched condition, as presently explained; the bottom of the basin is arranged to receive section D when in such lower position. Obviously, it is unnecessary for the section to swing through the complete arc to enable ships to be completely launched; hence, the bed of the basin is arranged to meet the conditions set up by the launching requirements of ships of a predetermined maximum size.

Each section D assembly is of positive buoyant characteristic, produced in any desired manner, as by the materials used, or by auxiliary means. As a result, the assembly will normally move to the upper end of the arc of swing when free to do so; and since the water level is in the vicinity of the top of the bulkhead, it will be understood that most if not all of the section will be submerged at all times.

In addition, the bottom face of the buoyant section of the supporting unit carries, in its outer zone, a planar face provided by flooring F, the flooring being secured to the under face of the truss structure at the outer end zone thereof; the flooring—and therefore the face—is of suitable width (in the drawings it is indicated as approximately one-third of the length of the lower face of the truss). The length of the flooring element is not limited to the width of the section—in practice it extends at least to and includes the width of the next section or unit, thus bridging the gap between adjacent units. As heretofore pointed out, the flooring may extend from unit to unit for as many as seven units to thereby provide a continuous face characteristic which would extend a distance which includes the overall distance provided by the included units, with the flooring itself serving to tie such units together to have their swinging movements in unison. If the number of supporting units employed is large, the element F may be in the form of a number of such unit groups, with the assurance that the units of a group will move together, through the connected relation produced by the flooring, and, during downward swing, providing concurrent downward movement of the unit groups, due to the fact that all of the groups underlie the ship, so that the movement of the latter causes the groups to have such concurrent movement; obviously, the element F could extend continuously from end to end of the assemblage regardless of the number of units, but this would tend to provide a somewhat unwieldy assemblage—hence, the unit grouping is preferred.

Aside from the tying together of a number of units for concurrent movement, flooring element F is designed especially as a retarding means active during the launching. As will be understood, when weight is placed on the buoyant section and thereby tends to swing it downward in its arcuate path, such movement must also move the flooring with the section; since the planar face extends at approximate right angles to the arc length, such planar face offers a large surface which must be moved bodily through the water as the arcuate movement develops, thus setting up a resistance characteristic tending to retard the advance. This resistance effect is not limited to the width of the truss but is present with the connecting portion of the element between adjacent units, so that the totality of face thus exposed approximately equals the overall distance of the assembled units times the width

of the element, an exposure total capable of providing a material resistance factor to the swinging movement of the section downward during the launching operation.

5 In launching service, the assemblage presents a number of highly important advantages, as will be understood from the following description of an assumed launching operation:

When the launching is to begin, and assuming the assemblage to be in the position of Fig. 1, it will be understood that when the usual chock blocks are removed, the weight of the ship will cause the sliding ways B to start travel down the fixed ground ways C; due to the angularity there will be a slight tendency to acceleration, but the rate is low. The continued advance of the sliding ways will cause their advance ends to pass over the hinging points d of sections D and on to such sections; however, until the vertical center line of the ship passes the hinging points d there is no material change in the conditions, since the preponderance of weight is then on the fixed ground ways. When the center line of the ship passes the hinging points, a preponderance of weight condition develops on the buoyant section side of the ways. This preponderance of weight is initially slight, due to the fact that only the difference in weight of the ship on opposite sides of a vertical plane through the hinging point is active as a weight factor on section D; as the sliding ways advance with the ship, this preponderance of weight grows through shifting weight from the land to the section side of the hinging point as the centerline of the ship advances, thus increasing the weight value of the section-borne side and reducing the weight value of the land-borne portion, this continuing until the sliding ways completely pass the hinging line.

40 As is apparent, the presence of the preponderance of weight as an active weight value on the buoyant sections, renders this preponderance of weight active as a weight factor tending to depress the submerged sections D. In the prior types of launching ships sidewise, this development and shift by the preponderance of weight has had the effect of rapidly changing the angle of advance of the ship; if the ship dropped off, the advance side would rapidly lower and thus rapidly shift the angularity of the center line relative to the vertical, so that the acceleration would be rapidly increased to a high value, with the result that the ship would contact the water high on the outboard side, after which righting 45 of the ship would produce the roll effect previously referred to. Practically similar results are produced where the ways are of the second type pointed out—the weight preponderance will rapidly shift the loose ways to their lower position, thus producing the rapid acceleration effect.

60 With the present invention, however, the effect is different. When the initial and small weight preponderance is made active on the buoyant sections D, the weight value is small and applied at the inner end of the sections; at this time the weight application is such as to set up the characteristics of a leverage system in which the power is being applied close to the fulcrum point and the power is opposed by a resistance made active 65 at the end of a lever arm which tends to oppose lowering of such arm. In other words, at this time the resistance value of the retarding means is high since it is being made active under leverage action. As a result, the development of the 70 arcuate movement of the outer end of the unit 75

section D is being actively retarded, so that the change in angularity of the section-borne ways changes at a slow rate and with consequent reduction in the rate of acceleration. It may be noted that at the instant the change in angularity of the section-borne ways begins, the portion of the sliding ways assemblage on the land side of the hinging point also becomes angular to the fixed ground ways, thus placing the weight of the inboard side of the ship in direct opposition with its tendency to control the rate of development of the preponderance of weight values. With the reduced acceleration, the shifting in angularity of the center line is at a low rate at the instant when the ship is actually approaching its water berth. Since the rate of acceleration is of slow increase at such time the sliding ways will continue to advance thus carrying the ship farther along toward the berthing point and away from the shore line.

As the preponderance of weight increases during the advance of the sliding ways, its weight value increases and at the same time the length of the resistance leverage arm decreases, thus tending to increase the angularity of the section-borne ways and the acceleration; hence, the power value is increased, as is the rate of acceleration, thus tending to increase the speed of advance of the outer end of the unit section in its downward arc. But this fact also provides the condition that the large area of the planar face of the retarding flooring F must advance a greater distance per unit of time, so that the resistance effect is not completely lost by the shortening of the leverage, but is tempered by the increase in resistance effect produced by the increased speed. As a result, while there is a continuing change in angularity of the section-borne ways, with a resulting increase in acceleration, the rate of increase in both is kept within reasonable limits.

As each increment in distance is added, there will be a constant increase in angularity of the section-borne ways and an increase in acceleration, but the rate at which these develop is materially reduced through the resistance provided by the retarding flooring F, as indicated. As a result, the ship will advance a greater distance from the bulkhead before contact with the water is had, as compared with the prior methods. And since each increment of advance carries the ship toward such contact with the water, the time comes when the actual contact adds its effect through resistance provided by ship displacement of the water, thus tending to decrease the power value being exerted on the leverage arm—the ship's water displacing resistance is added to that of the flooring F, as a control agency in the downward movement of the section, to thus control the rate of acceleration. Hence, the launching of the ship will be at a more uniform rate increase as to acceleration, with the angle of the center line of the ship to the vertical greatly reduced in value—thus reducing the possible rolling value—and with the distance from the bulkhead increased, to render the ship immune from inboard damage value.

In other words, the effect of the presence of flooring F together with its particular location relative to the pivot point of the section is primarily to damp the sudden change that occurs at the instant when the preponderance of weight becomes active to change the angularity of the center line of the ship; in practicing the prior methods, the change in the angularity of the

center line through change in angularity of the ways is sudden and abrupt with consequent rapid increase in the rate of acceleration, thus tending to set up the conditions of falling rather than of a controlled advance. As a result, the present invention, while setting up the characteristics of acceleration, tends to retain the rate of increase of acceleration within greater control and with lessened shift of the center line of the ship from the vertical; in this respect the launching has more of the orderliness of the lengthwise launching procedure, rather than the broadside characteristic that is present with sidewise launching and which inherently tends to provide for abrupt changes in the accelerating conditions and the tendency to set up the "drop" or "falling" condition during the period of approach of the ship to the surface of the water. While the present invention will provide constant acceleration until contact is had with the water, the damping effect provided during this critical period tends to retain the rate within controllable limits in contrast with the sudden changes that are inherent with the prior methods.

As will be understood, the axes of the hinging points of all of the supporting units of the assembly are in alignment, since all of the units must begin their swing at the same instant; and it is obvious that the chocking of the sliding way assemblage should be arranged in such manner that the advancing movement of such assemblage over the fixed ground ways will bring the center line of the ship over the hinging points at the same instant to ensure the most favorable conditions in launching.

When the launching is completed and the ship is moved from the zone of the ways, the buoyancy of sections D will raise them to their upper positions; the sliding way assemblage may or may not remain on the sections at such time, but will, in either event, be brought to the surface to be collected for re-use. While the retarding flooring F may tend to delay the time-length of return of the sections to their upper positions, this is immaterial since the sections remain inactive until the succeeding launching.

The basin E, in the vicinity of the bulkhead has its bed fashioned to receive the depressed sections, as indicated by the showing of Fig. 1; and may actually be given the inclination shown in this figure to present a stop characteristic to limit the downward movement of the section and prevent strain on the hinging points should the sections be used for launching very large ships—the inclined bed would form a definite limit to the angularity to which the buoyant ways could move; since this stop effect would take place when the ship has reached the water, and the angularity of the ways established, a ship of great depth of keel could continue to advance until buoyancy is reached and without further change in the angularity of the center line; both the ship and the ways would thus be protected. However, in practice, the completed launchings will generally be over before such position is reached, it being understood that the earlier completion will reduce the angularity of the ship's center line to the vertical correspondingly—one of the advantages of the present invention.

For instance, a ship of small tonnage will obviously present a smaller weight factor as well as require less depth of water in launching; obviously, such a ship will develop a lower rate of

downward movement of the sections D, thus lowering the rate of acceleration increase, and at the same time complete the launching with the angularity of the section ways less variant from the horizontal than with a larger ship, with resultant difference in the angularity of the center line. In other words, with the installation of a complete battery of units, the yard is equipped to handle the launching of ships of all sizes under sufficient launching conditions.

Another advantage is found in the possibilities presented for shipyard operations on the basis of ships of uniform dimensions. Under such conditions it is possible to accurately determine the needed area of the flooring F to ensure a desired retarding action, and thereby ensure similar launching conditions for each ship. If it is found necessary to change such area to meet the conditions of production of ships of larger or smaller dimensions, the area can be varied by increasing or diminishing the width of the flooring zone; by the use of a suitable connection between the lower end of the tethering cable and bed-anchor, it would be possible to disconnect the section D from its anchor, thus permitting the section to rise to the surface for making such changes in flooring width as well as making repairs.

As heretofore pointed out, the sliding ways may be individual to a supporting unit, to a succession of such units, or may include all of the units, this being determined by the length dimension of the way, the practice at the yard in this respect being utilized; in either form the arrangement is considered as a sliding way assemblage.

The specific structure of the buoyant section shown in the drawings is intended simply as illustrative, being shown as of truss characteristic. In practice, any suitable detail structure may be employed, it being essential that it be hingedly-supported at its inner end, tethered at its outer end to the bed of the basin to limit the upward movement of the section while permitting downward swinging through an arc, and to have positive buoyancy sufficient at least to normally retain the section in its upper position. These characteristics, together with the retarding means F, are essential.

While I have herein shown and described one or more forms of assembly for providing sidewise launching of ships, it will be readily understood that changes or modifications thereof may be found desirable or essential in meeting the varied installation and operational needs or the individual desires of the user, and I therefore reserve the right to make any and all such changes or modifications therein as may be found essential or desirable in meeting these conditions, insofar as the same may fall within the spirit and scope of the invention as expressed in the accompanying claims when broadly construed.

What is claimed as new is:

1. In assemblages for sidewise gravitation launching of ships, and in combination, a sliding way assemblage for supporting the ship during launching, and a plurality of supporting units arranged in spaced parallelism relative to the bulkhead of the launching basin and over which the laden sliding way assemblage advances down-

wardly by gravitation in an inclined path of movement during the launching operation, each of such supporting units including a fixed ground way formation extending substantially to the bulkhead and a buoyant section of positive buoyancy hinged relative to such formation with the hinging point located at such bulkhead position, the buoyant section having its outer end tethered to the bed of the basin to limit the upward movement of the section and to permit freedom of downward arcuate swinging of the section about such hinging point, each ground way formation and buoyant section combinedly presenting a gravitational downwardly-inclined way extending in a substantially common plane prior to the ship's launching, the plane of the buoyant section being varied downwardly relative to such plane during the launching movement of the ship and by and due to the weight of the ship and sliding way assemblage, and retarding means carried by and movable with such buoyant section, said means being rendered active during launching by advance of the laden sliding way assemblage relative to the buoyant section and being operative to damp the rate of acceleration of the laden assemblage over the section.

2. A launching assemblage as in claim 1 characterized in that the retarding means includes a planar face carried by the outer end zone of the under face of the section and extending substantially normal to the direction of arcuate swing of the section.

3. A launching assemblage as in claim 1 characterized in that the retarding means includes a planar face carried by the outer end zone of the under side of the section and extending substantially normal to the direction of arcuate swing of the section, and with the face of predetermined width and of a length sufficient to include at least two adjacent buoyant sections.

4. A launching assemblage as in claim 1 characterized in that the retarding means includes a planar face carried by the outer end zone of the under side of the section and extending substantially normal to the direction of arcuate swing of the section, and with the face of predetermined width and of a length sufficient to connect a plurality of adjacent buoyant sections into an assembly of buoyant sections movable bodily as a unit.

5. A launching assemblage as in claim 1 characterized in that the retarding means includes a planar face carried by the outer end zone of the under side of the section and extending substantially normal to the direction of arcuate swing of the section, and with the face of predetermined width and of a length sufficient to connect a plurality of adjacent buoyant sections into an assembly of buoyant sections movable bodily as a unit, with the number of latter units determined by the totality of supporting units active in the launching operation.

6. A launching assemblage as in claim 1 characterized in that the sliding way assemblage is formed of a succession of individual sliding way units equaling the number of supporting units, with each sliding way unit individual to a supporting unit.

BLAKELY SMITH.
